UNITED STATES PATENT OFFICE.

EMMA H. STONEER, OF ENID, OKLAHOMA.

CARPET BEATER.

1,418,179.

Specification of Letters Patent. Patented May 30, 1922.

Application filed March 2, 1921. Serial No. 449,010.

To all whom it may concern:

Be it known that I, EMMA H. STONER, a citizen of the United States, residing at Enid, in the county of Garfield and State of Oklahoma, have invented certain new and useful Improvements in Carpet Beaters; and I do declare the following to be a full, clear, and exact description of the invention, such as will enable others skilled in the art to which it appertains to make and use the same.

This invention relates to an improved carpet beater of the type having carpet beating elements and one object of the invention is 15 to provide improved means for mounting and actuating the beaters, the actuating means being so constructed that the beaters will be lifted and then released and permitted to drop of their own weight into striking engagement with a carpet placed upon a supporting table beneath the beaters.

Another object of the invention is to so construct the operating means for the beaters that the beater engaging elements may 25 be held in an operative position by resilient means and moved to release the beaters by cam means which will move the beater engaging elements to an inoperative position against the action of the resilient means, 30 holding them in an operative position.

Another object of the invention is to so construct the device that the beaters may be loosely mounted upon a shaft carrying the beater engaging means and thus the shaft 35 for each beater serves not only as means for pivotally mounting the beater but also as means for rotatably mounting the beater engaging elements.

Another object of the invention is to provide 40 an improved carpet beater in which the beaters may be movably mounted in a housing above a perforated carpet carrying table beneath which will be positioned a fan for drawing the loosened dirt and dust out of 45 the carpet.

Another object of the invention is to so construct this carpet beating machine that the beater elements may be mounted upon shafts at opposite sides of the machine, the 50 two shafts carrying the beaters and actuating elements thereof, being driven from a common drive shaft extending beneath the receptacle or body and having geared connection with the fan positioned beneath the 55 carpet carrying table.

Another object of the invention is to provide a carpet beater which will be comparatively simple in construction and very efficient in operation.

This invention is illustrated in the accompanying drawings, wherein:

Figure 1 is a top plan view of the improved carpet beating machine.

Figure 2 is a view showing the improved machine in side elevation, one wall of the housing being broken away.

Figure 3 is a transverse sectional view through the machine taken along the line 3—3 of Fig. 2.

Figure 4 is an enlarged view taken along the line 4—4 of Fig. 2.

Figure 5 is an enlarged top plan view of one corner portion of the carpet beating machine.

Figure 6 is a sectional view taken along the line 6—6 of Fig. 5 with the beater about to be moved upwardly.

Figure 7 is a view similar to Fig. 6 showing the beater swung upwardly and the beater engaging elements about to be moved out of engagement with the beater.

Figure 8 is a sectional view taken along the line 8—8 of Fig. 5.

This improved carpet beating machine is provided with a receptacle or body 1 which may be provided with a cover if desired and is supported upon supporting legs or standards 2, the supporting legs being connected by bars 3 which extend beneath the receptacle 1 in crossed relation as shown in Fig. 4 and carry a cage or frame 4 which is held in place by bolts 5 and 6. This cage 4 is of a construction clearly shown in Figs. 3 and 4

and is provided with a lower plate 7 having arms 8 through which the bolts 5 pass and an upper plate 9 connected with the bottom of the receptacle by the bolts 6 and connected with the lower plate 7 by the standards 10. The cage 4 fills the space between the cross bars 3 and the bottom of the receptacle and thus provides a brace for the central portion of the receptacle as well as

providing a gear housing in which will be positioned the gears 12, 13 and 14. The gear 12 is carried by a vertically disposed shaft 15 which is journalled in the bottom of the receptacle and has its upper end portion within the receptacle carrying a fan 16.

The gears 13 and 14 are carried by the shafts 17 and 18 which have their inner end por-

110

tions mounted in bearings 19 carried by the frame 4. The shafts 17 and 18 extend outwardly and each carries a pulley wheel 20, the shaft 17 in addition to its pulley 20, carries a pulley 21 about which will pass a belt 22 leading from a suitable source of power so that the shaft 17 may be rotated.

Within the housing or receptacle is placed a table or carpet carrying element 23 having a top 24 which is perforated and preferably formed of woven wire fabric as shown in Fig. 3. Shafts 25 are rotatably mounted in bearings 26 and extend longitudinally of the receptacle adjacent opposite walls thereof and above the carpet carrying table 23. Each of these shafts 25 has one end portion extending through the adjacent end wall of the receptacle and upon the outer end portion of each shaft is mounted a pulley wheel 27 so that rotary movement can be transmitted to these shafts by the means of belts 28 which pass about the pulley wheels 20 and pulley wheels 27. A beater board 29 is connected with each of the shafts 25 by bearing plates 30 and 31, the bearings of these plates fitting loosely upon the shaft so that the beater board may swing freely upon the shaft. Each of these boards is formed of thin material and will be provided with openings 32 for the sake of lightness and to permit the boards to swing freely without their action being interfered with by air resistance. It will thus be seen that the beater boards will have movement independent of the shafts 25 and that these boards may be swung upwardly and then released and may drop back to strike the carpet which will be placed upon the table 23 by their own weight.

In order to swing the beater boards upwardly, the bearing plate 31 of each board is provided with a finger extension 33 which constitutes an abutment finger for engagement by the hook or pawl 34 which is pivotally connected with the disk 35 by means of a bolt or other suitable pivot fastener 36. This disk 35 is rigid upon the shaft 25 and therefore as the shaft and disk rotate, the hooked end of the pawl will be brought into engagement with the abutment finger 33 once for each revolution of the shaft. This pawl is yieldably held in an extended or operative position by means of the springs 37 and is limited in its outward movement through engagement with the block 38 which is carried by the disk for engagement by the extension 39 of the pawl, as shown in Fig. 8. From an inspection of this Fig. 8 and also Figs. 6 and 7, it will be seen that the heel portion of the pawl extends beyond the periphery of the disk and is curved longitudinally thus providing a cam surface 40 for engagement by the cam 41 which is in the form of a bracket secured to the wall of the receptacle by a bolt or other similar fastener 42. From a comparison of Figs. 6 and 7, it

will be readily seen that as the shaft 25 rotates, the hook or pawl will first engage the finger 33 and cause the beater board to be swung upwardly. The cam extension of the pawl will then come in contact with the cam 41 as shown in Fig. 7 and as the shaft continues to rotate, this pawl will be forced inwardly against the action of the spring 37 thus moving the pawl or hook out of engagement with the finger 33 and releasing the beater board so that the beater board may fall back of its own weight and strike against the carpet which will be placed upon the table 23. As soon as the pawl or hook moves out of engagement with the cam 41, the spring will return the pawl to the extended position shown in Fig. 8 and the pawl will again be in position for engaging the abutment finger of the beater board. The fan which is rotated from the shaft 17 by means of the cooperating gears 12 and 13 will rotate beneath the table and cause a draft so as to remove the dirt and dust from the carpet. If desired, springs may be connected with the beater boards so that they may be pulled down into the striking position of Fig. 3 when released.

What is claimed is:

1. A carpet beater comprising a receptacle, a perforated carpet support in said receptacle, a driven shaft extending through said receptacle, a beater loosely mounted upon said driven shaft, a disk rigid upon said driven shaft, a pawl pivotally carried by said disk, resilient means yieldably holding said pawl in a position for engaging said beater thereby swinging the beater upwardly as the driven shaft rotates, means for moving said pawl out of engagement with said beater as the shaft rotates, and a fan beneath said carpet support. 95

2. A carpet beater comprising a carpet support, a carpet beater loosely mounted for swinging movement, a rotatable carrier, a beater engaging element movably associated with said carrier and yieldably held in position for engaging said beater, and means for moving said beater engaging element out of engagement with said beater as the carrier rotates. 110

3. A carpet beating machine comprising a carpet support, a rotatable shaft, a beater loosely mounted upon the shaft for vertical swinging movement above said support, an abutment extending from said beater, a carrier rigid upon said shaft, a pawl pivotally connected with said carrier and having a hooked free end portion for engaging said abutment, one portion of said pawl extending beyond said carrier and providing a cam surface, resilient means yieldably holding the pawl in an extended position for engagement with said abutment, and means for engaging the cam portion of said pawl for moving the pawl out of engagement with the 125

abutment and releasing said beater as the shaft rotates.

4. A carpet beating machine comprising a carpet support, a rotatable shaft, a beater element above said carpet support, bearing brackets carried by said beater and loosely mounted upon said shaft, one of the brackets having an abutment pin extending therefrom beyond the beater, a disk rigid upon said shaft, a pawl pivotally connected with said disk and having a hooked end portion for engaging said pin extension, a heel end portion on said pawl extending beyond the periphery of said disk and curved longitudinally to provide a cam surface, and a cam element mounted for engaging the cam surface of said pawl and moving the pawl inwardly against the action of said resilient means out of engagement with said pin extension to release said beater as said shaft rotates.

5. A carpet cleaning machine comprising a housing, a carpet support in the housing, driven shafts rotatably mounted in said housing, beaters loosely mounted upon said shafts above said carpet support, means carried by said shafts for releasably engaging said beaters to swing the beaters upwardly, means for moving the beater engaging means out of engagement with the same, a fan positioned beneath said carpet support and having a shaft journaled in the bottom of said housing, said shaft being in geared connection with the fan shaft and having connection with the driven shafts, and means for driving one of the last mentioned shafts.

6. A carpet cleaning machine comprising

a housing, a carpet supporting table in said housing having a perforated carpet engaging surface, beating means above said table including shafts extending externally of said housing, a fan beneath the table having a shaft extending through the bottom thereof, supporting legs for said housing, cross bars connecting said supporting legs, a frame positioned beneath the housing and engaging said cross bars and the bottom of the housing and constituting a gear housing and support for the bottom of said housing, shafts positioned beneath the housing upon opposite sides of the fan shaft, gears carried by the lower portion of said fan shaft and the inner ends of said last mentioned shafts and meshing for transmitting rotary movement to said fan shaft, means for transmitting rotary movement from the last mentioned shaft to the shafts of the beating means, one of the shafts beneath the housing constituting a driving shaft, and means for rotating said driving shaft.

7. A carpet cleaning machine comprising a carpet support, a driven shaft rotatably mounted, a beater loosely mounted upon said shaft above said carpet support, means carried by said shaft for releasably engaging said beater to swing the beater upwardly, and means for moving the beater engaging means out of engagement with the beater as the shaft rotates, the beater when released moving into striking engagement with a carpet upon the carpet support.

In testimony whereof I have hereunto set my hand.

EMMA H. STONER.
